HEATER

Francis C. Williams, Dearborn, Mich.

Application April 23, 1937, Serial No. 138,606

2 Claims. (Cl. 126—110)

The present invention relates to heating appliances or more particularly to that type of furnace commonly known as a salamander, wherein the products of combustion are circulated directly throughout the area to be heated.

It is an object of the present invention to provide a heating unit for heating large areas rapidly and with relatively low consumption of inexpensive fuel.

10 A further object of the invention is the provision of a heating unit in which the products of combustion of the fuel are circulated throughout the area to be heated but in which pure air is mixed with said products of combustion in 15 such proportions that the deleterious constituents thereof such, for example, as carbon monoxide will be present only in such small amounts as will be perfectly harmless.

15 A further object of the invention is the provision in a device of this character of means for regulating the proportion of pure air circulated and the rate of consumption of fuel and hence the rate of heat output.

20 A still further object of the invention is the provision of means for so circulating the air that is to be mixed with the outgoing products of combustion as to cause a preheating thereof and at the same time a cooling of those portions of the unit which might otherwise be damaged 25 by the excessive heat resulting from consumption of fuel therein.

25 One form of my invention is exemplified in the accompanying drawings and described in detail in the following specification wherein further of its objects and advantages are made apparent.

In the drawings:

Fig. 1 is a central vertical section of a heating unit embodying my invention.

40 Fig. 2 is a sectional view taken on the line II—II of Fig. 1.

Fig. 3 is a similar section taken on the line III—III of Fig. 1.

Fig. 4 is a vertical transverse section taken 45 on line IV—IV of Fig. 3, and

Fig. 5 is a section similar to that shown in Fig. 3 and illustrating a modified form of the invention.

50 Referring more particularly to the drawings, the invention is illustrated as comprising a rectangular metal housing generally indicated at 10, the walls of which may be formed about any suitable framing structure or if desired may be formed of sufficiently rigid material to support 55 themselves. The housing 10 may be supported

upon a hollow metallic base 11 which forms an air space sufficient to provide an insulation that will prevent damage to a floor of wood or other inflammable composition. Centrally within the housing 10 is a vertically extending fuel magazine 12 adjacent the lower end of which is a grate comprising grate bars 13 supported at their opposite ends by trunnions 14, the rear trunnions of the grate bars 13 extend through the back wall of the magazine 12 behind which wall they 10 are provided with intermeshing gears 15. These trunnions are further extended through the back walls 10 where the outer ends of one or more of them may be squared, as shown, for the reception of a removable wrench which may be employed to oscillate the grate bars thus agitating the material supported by them and causing the residual products of combustion to fall between them to the bottom of the magazine.

55 Approximately centrally of the housing and horizontally disposed forwardly and on two sides of the magazine 12 is a partition 16. The upper compartment formed by the partition 16 communicates by means of an opening 17 (see Figs. 2 and 4) with a blower unit comprising a housing 18, a motor 19, and rotor 20 supported and driven by said motor. The rotor 20 when driven by the motor draws air through an intake 21 and expels it through the opening 17. The greater portion of the air thus put into circulation by the blower is caused to pass around the upper end of the magazine 12 above the partition 16 and is then forced downwardly where it passes forwardly on both sides of the lower end of the magazine and is permitted to escape through an outlet 24 provided for this purpose at the forward face of the housing.

40 In order to provide air in any desired quantity to support and regulate combustion of fuel in the magazine 12 a hinged damper 25 is arranged rearwardly of the fuel magazine and in a position to intercept the draft of air from the blower and direct a portion thereof downwardly through a grill 26 and through a suitable opening 27 in the lower-most portion of the rear wall 45 of the fuel magazine so that it may pass upwardly between the bars of the grate and out through the opening 24. A screen 28 is preferably provided to filter the products of combustion thus passing through the opening 24 to prevent 50 burning embers or the like from passing into the area to be heated. The damper 25 is provided with an operating lever 29 on a shaft 30 which extends through the housing and carries a crank arm 31 at its inner end connected by a 55

link 32 with the damper, so that upon rotation of the lever 29 the damper may be adjusted and the quantity of air deflected thereby to pass directly through the fuel magazine may be varied.

5 The upper portion of the rear wall of the fuel magazine may be provided with an air inlet in the form of a plurality of perforations such as shown at 33 in Fig. 4. The air intake is preferably arranged directly in line with the blast of air entering the housing 17 so that a small portion of the air will pass into the upper end of the fuel magazine and create a pressure therein sufficient to drive downwardly any fumes that may have a tendency to rise causing these fumes to remain in the area of greatest heat until complete combustion has occurred and they pass out through the opening 24 in front of the housing.

10 The fuel magazine extends upwardly through the top of the housing and is provided at its upper end with a durable cover number 35 which may be securely fastened thereon to prevent the escape of gases by means of rotatable handles 36 having bevelled lugs 37 formed at their lower ends to engage upon being rotated with ears 25 38 fixed to the inner walls of the magazine.

15 That portion of the fuel magazine directly above the grate is preferably surrounded by refractory tile as indicated at 39 to prevent unnecessary radiation of heat and to serve as an insulation and protector for other portions of the unit.

20 As a further precaution against radiation of heat causing the side walls of the housing to become overheated and thereby warped or discolored it is desirable that baffles 40 be provided 25 to divide the compartment below the horizontal partition 16 into horizontally extending channels thus permitting free passage of air from the rear to the forward end of this compartment and preventing undue radiation of heat to the outer 30 walls of the housing.

25 Curved plates 41 as illustrated in Figs. 2 and 3 may also be provided at the forward corners to direct the air centrally of the forward end of the housing so that it will pass freely through 35 the opening 24.

30 To operate the heating unit a fuel such, for example, as coke is stacked in the magazine until it is substantially full and the fuel is caused to burn at the bottom of the stack adjacent the 40 grate 13. To obtain combustion of the fuel at this point a wood fire is first started on the grate with the cover of the magazine removed and a small covering of coke is placed over the wood fire until the coke is well caught. At this time 45 the blower which may be used to incite ready combustion of the wood and coke is cut off, the magazine stacked with coke and the cover securely clamped in position.

45 The air forced through the openings 33 in the upper portion of the magazine and the cool air circulated about the exterior thereof maintain the temperature of the coke in the upper portion below the point of combustion and as that portion being burned on the grate deteriorates and gives 50 way the stack in the magazine moves downwardly under the force of gravity providing an automatic feed of fuel to the area of combustion.

55 The blower draws in fresh air usually from within the building in which the unit is operating but if the building is relatively small or comparatively air tight an extension may be placed over the blower inlet and led to the exterior of the building to obtain fresh air. The greater portion of the air passes around the magazine as 60 70 has been described while that portion necessary

5 to produce the desired amount of heat and the desired rate of fuel combustion is directed into the fuel magazine by the means of the adjustable damper 25. The air circulating about the magazine then passes downwardly and forwardly below the horizontal partition 16 and is forcibly discharged through the opening 24 in front of the housing not only mixing with and carrying with it the products of combustion from the fuel magazine but causing somewhat of a Venturi action 10 thus forcibly expelling the heated fumes from the magazine and preventing undue concentration of heat and consequent radiation which would have a destructive effect upon the unit itself.

15 A heating unit thus constructed is capable of rapid and highly efficient heating of large areas as an inexpensive fuel may be burned at any desired rate and with substantially one hundred per cent of efficiency as practically all of the 20 heat is forcibly directed over the required area. Owing to the large quantity of fresh air continually mixed with the product of combustion from the fuel magazine the proportion of noxious gases in the output of the unit is so small as to be 25 negligible. However, if it is desired to heat relatively small enclosed areas where the presence of even a small percentage of carbon monoxide or other noxious gases would be undesirable, the forward opening of the combustion magazine may 30 communicate with a radiator such as is illustrated at 42 in the modification shown in Fig. 5, and this radiator may comprise vertically spaced tubes 43 positioned in front of the outlet opening of the unit so that the products of combustion 35 may be carried through these tubes to a suitable flue and directed to the open atmosphere. The air circulated about the magazine will pass over and between the radiator tubes 43 thus absorbing their heat without mixing with the undesirable 40 products of combustion.

45 Heating units of this character may be conveniently mounted upon trucks so that they are readily portable or may be provided with large eye bolts permitting them to be conveniently moved about by a crane and are thus well adapted to use in heating portions of large plants where men are at work to provide comfort for the workers and in many instances to maintain special materials in workable condition.

50 Heating units constructed in accordance with my invention are also suitable for "warming up" internal combustion engines as well as other machinery where a moderate or high temperature is necessary to create favorable operating condition.

55 While a preferred embodiment of my invention has been illustrated and described, it is, of course, to be understood that various changes may be resorted to in the construction and arrangement 60 of its several parts within the scope of the appended claims.

65 What I claim and desire to secure by Letters Patent is:

1. A direct heat furnace comprising a rectangular housing, a fuel magazine arranged centrally and vertically within the housing, a generally horizontal partition in front of and on two sides of the fuel magazine dividing the housing into an upper and a lower compartment, said housing 70 having a forward opening in communication with the lower compartment and an opening from said lower compartment into the combustion chamber of the fuel magazine, a blower carried at the rear of the housing to force air into the upper com- 75

- partment whereby air will be circulated around the upper end of the magazine then downwardly and forwardly in the lower compartment to pass outwardly through the opening in the housing 5 an adjustable damper to intercept the air entering the housing, means to direct the air deflected by the damper into the lower end of the fuel magazine, and means for permitting a portion of the air entering the housing to enter the upper 10 end of the fuel magazine.
2. In a heater, a housing; a plurality of plates in said housing attached to the inner walls thereof and cooperating with each other to close a fuel magazine, said plates dividing the space between the housing and fuel magazine into upper and lower compartments, there being an opening in 15 the housing into the lower compartment and an opening from said lower compartment into the combustion chamber of the fuel magazine; an air blower carried by the housing to force air into the upper compartment whereby said air will be circulated around the outside of the upper end of the fuel magazine, then downwardly into the lower compartment; an adjustable damper to intercept the air entering the housing; means to direct the air deflected by the damper into the lower end of the fuel magazine; and means for 10 by-passing a portion of the air entering the housing into the upper end of the fuel magazine to create a pressure therein sufficient to force the still combustible components of the products of combustion into contact with the furnace to 15 cause the burning thereof.

FRANCIS C. WILLIAMS.
